UNITED STATES PATENT OFFICE.

BARRY IVOR, OF CHICAGO, ILLINOIS

CARBURETER.

976,881.

Specification of Letters Patent. Patented Nov. 29, 1910.

Application filed January 13, 1910. Serial No. 537,872.

To all whom it may concern:

Be it known that I, BARRY IVOR, a citizen of the United States, residing at Chicago, in the county of Cook and State of Illinois, have invented certain new and useful Improvements in Carbureters, of which the following is a specification.

This invention relates to improvements in an apparatus to be used in connection with hydrocarbon-engines for the purpose of charging air or gas with volatilized hydrocarbons and supplying the same to the engines, and while it is more especially intended to be used in connection with gasolene engines for operating automobiles, yet it is also applicable for use in connection with other kinds of hydrocarbon-engines used for other purposes, and it consists in certain peculiarities of the construction, novel arrangement and operation of the various parts thereof, as will be hereinafter more fully set forth and specifically claimed.

The principal object of this invention like that of a pending application Number 545,868, filed by me on February 25, 1910, for improvements in carbureters, is to provide a carbureter which shall be simple and inexpensive in construction, strong, durable and effective in operation, and so made as to dispense with the use of the ordinary float valve which is commonly employed in the carbureters heretofore in general use, and the use of which valves is objectionable for the reason said float valves are liable to clog, to be misplaced by the vibrations of the machine, and to permit of flooding or undercharging the engine.

Another object of the invention is to produce a carbureter which will more thoroughly unite or commingle the air and hydrocarbons, than is ordinarily done, and will prevent waste of gasolene or hydrocarbons.

Other objects and advantages of the invention will be disclosed in the subjoined description and explanation.

In order to enable others skilled in the art to which my invention pertains, to make and use the same, I will now proceed to describe it referring to the accompanying drawings, in which—

Figure 1, is a central vertical sectional view of a carbureter embodying the invention. Fig. 2, is a plan view of the body casing or cylinder with the mixing chamber removed therefrom, showing the means of supporting the gasolene reservoir and force

feed pump for the gasolene therein. Fig. 3, is a vertical sectional view of a portion of the carbureter showing the means for supporting parts of the pump therein. Fig. 4, is a plan view of the air supply regulating means or lower portion of the device. Fig. 5, is a fragmental view of a portion of the body casing or cylinder and a part of the mixing chamber showing a modification in the construction of the means for the passage of air from the body casing to the mixing chamber. Fig. 6, is a fragmental plan view of a portion of one of the valves of the air chamber.

Like numerals of reference, refer to corresponding parts throughout the different views of the drawings.

The reference numeral 10, designates the body or main cylinder of the device and has on its upper end an out-turned annular flange 11, provided with a series of openings 12, for the reception of screw-bolts 13, used for securing the casing 14, of the mixing chamber on said flange. As shown in Figs. 1, and 2, of the drawings, the body or cylinder 10, is provided within its cavity with a receptacle 15, which is preferably substantially bell-shaped as shown, but may be of any desired form and is held at a distance from the inner walls of the casing or cylinder 10, by means of lugs 16, which unite the two parts 10, and 15, about midway between their upper and lower ends. The said parts may be formed integrally if desired, and one of the lugs or extensions 16, is provided in its outer portion with a screw-threaded opening 17, from which a port 18, leads into the cavity of the receptacle 15, or inner casing, which has its upper portion contracted and provided with a screw-threaded opening. The lower end of the receptacle 15, is internally screw-threaded to engage screw-threads on the base 19, of the pump cylinder 20, for the gasolene, which cylinder has its upper portion externally screw-threaded to engage the contracted upper portion of the inner casing 15, as will be readily understood by reference to Fig. 1, of the drawings. The pump cylinder 20, is provided with a cavity 21, which is extended from its lower end upwardly to a suitable point and has movably fitted therein a piston or plunger 22, which is extended below the base of the pump cylinder for the purpose to be presently explained.

Leading from the upper end of the cavity

21, in the pump cylinder is a channel 23, which terminates at its upper end in an enlarged opening 24, formed in the upper end of the cylinder 20, and provided with internal screw-threads to engage screw-threads on the lower portion of a spreader 25, for the gasolene, which spreader is preferably conical in shape and has a peripheral upturned flange 26, to form a receptacle for the retention of a quantity of gasoline. The spreader 25, is provided in its lower portion with a vertical opening 27, in which is located a ball-valve 28, normally seated in the upper end of the channel 23, and held in its seated position by means of a spring 29, located in the opening 27, and resting at one of its ends on said ball and at its other end against the upper end of said opening. Communicating with the opening 27, and extended through the apex of the spreader 25, is another opening 30, which forms a seat for a needle valve 31, used for regulating the flow of gasoline to the mixing chamber. Communicating with the opening 27, and extended to one side thereof and through the lower portion of the spreader 25, is a channel 32, which communicates with a channel 33, formed in the upper portion of the pump cylinder 20, and extended downwardly therein to a point below the upper end of the casing or receptacle 15, at which point it communicates through an opening 34, with the cavity of the said receptacle. Seated in the upper portion of the opening 33, is a ball-valve 35, which is held in its seated position by means of a spring 36, which rests at one of its ends against the bottom of the opening 33, and at its other end against the ball-valve 35. The lower portion of the base 19, of the pump cylinder is provided with a vertical opening 37, which is internally screw-threaded to engage screw-threads on a plug 38, which is provided in its upper end with an opening 39, having a reduced channel 40, extended from the lower part thereof, out through one side of the plug and communicating with a port 41, formed in the side of the pump cylinder just above the base portion thereof.

50 Leading from the upper end of the opening 37, is a channel 42, which communicates at its other end with the upper portion of the cavity 21, for the piston or plunger of the pump. Located in the opening 39, and seated in the upper end of the channel 40, is a ball-valve 43, which controls the flow of gasolene from the receptacle 15, into the cavity of the pump cylinder. Secured on the lower portion of the body casing or main cylinder 10, is a cup 44, which is provided in its walls with a series of openings 45, for the passage of air thereinto, and has in its lower portion a series of openings 46, controlled by gravity valves 47, which openings are also for the admission of air. As shown in Fig. 1, the piston or plunger 22, is extended through an opening in the bottom of the cup 44, and has its lower end screw-threaded and provided with nuts 48, to regulate its stroke. Rotatably fitted in the cup 44, is a ring 49, which is provided with a series of openings 50, adapted to register with the openings 45, in said cup, yet which may be turned out of register therewith or partially so by means of a projection 51, which is secured on the ring 49, and extended through a slot 52, formed in the wall of the cup. Horizontally mounted on the plunger 22, between the bottom of the cup 44, and the base portion of the pump cylinder, is a bar 53, through an opening in each end of which is passed a rod 54, which rods are extended upwardly through openings 55, in the diametrically disposed lugs 16, which unite the casing 10, and the receptacle 15, and engage at their upper ends a disk or plate valve 56, which rests on the top of the casing or cylinder 10, and has on its lower surface an annular flange 57, which fits snugly in the cylinder 10, and is provided with openings 58, for the passage of air therefrom. Thus it will be seen that the plunger and valve 56, are connected together by means of the rods 54, and that said parts will move in unison.

55 Located on the flange 11, of the cylinder or casing 10, is the casing 14, of a mixing chamber 59, which casing will be secured in place by means of the screw bolts 13, as before stated. The lower inner portion of the casing 14, fits snugly around the valve 56, yet so as to permit of its vertical movement, for it will be understood that said valve is provided with a central opening 60, to fit around the upper portion of the pump cylinder which is rigidly held in place within the casing 15, by means of its screw engagement therewith, as well as by means of a lock nut 61, located thereon, just below the valve 56, which valve is provided near its periphery with a series of inwardly and upwardly directed ports 62, for the passage of air from the cylinder 10, to the mixing chamber. Leading from the upper portion of the casing 14, is a conduit 63, which may be suitably connected to the engine (not shown) and which may be provided with a damper 64, of any well known type to regulate the passage of the mixture of air and gasolene from the mixing chamber to the engine. Mounted in the upper portion of the conduit 63, in any well known way, is a needle valve 31, which is adapted at its lower end to open and close the port 30, in the spreader 25, and has on its lower portion a baffle 65, for the gasolene and air as they are discharged from and above the spreader. Located around the valve 31, and preferably secured to the casing 14, at its point of connection, with the conduit 63, is a perforated

60 65 70 75 80 85 90 95 100 105 110 115 120 125 130

baffle 66, which will assist in causing the commingling of air and hydrocarbons. The casing 14, is preferably provided with a safety-valve 67, of any well known type to prevent damage in case of back pressure from the engine, or an explosion in the mixing chamber.

Secured in the opening 17, of the casing or cylinder 10, is a fitting 68, which is provided with an inlet channel 69, communicating with the port or opening 18, for the supply of gasoline to the receptacle 15, which channel may have communication through a pipe 70, with a supply of gasoline (not shown). The fitting 68, is provided with a pin valve 71, adapted to be seated in the channel 69, for regulating the supply of gasoline to the receptacle therefor. Intersecting the channel 69, is an opening 72, in which is fitted a tube 73, which has at its upper end a sieve 74, of wire gauze or other suitable material to strain the gasoline as it passes through the channel 69, into its receptacle. The lower end of the tube 73, is closed by means of a screw-plug 75, engaging the lower end of the extension 76, formed on the fitting 68, and communicating with the opening 72, thereof.

In Fig. 5, of the drawings is shown a modification in the construction of the upper portion of the cylinder or casing 10, and in the construction of the valve 56, therefor which consists in providing the upper inner portion of the cylinder 10, with a series of ports 77, which when the valve 56, is raised sufficiently to allow the flange 57, thereof to open said ports, will permit air to pass therethrough and from thence through the ports 62, of the valve into the mixing chamber. It will be observed that in this modified construction the openings in the flange 57, of the valve are omitted.

The operation of the device is as follows:— Gasoline or other hydrocarbons is supplied to the receptacle 15, through the channels 69, of the fitting 68, and through the port 18, of said receptacle, when through the suction or operation of the engine, the valve 56, will be raised within the mixing chamber until the openings 58, are placed in communication with the lower portion of said chamber, at which time, air will pass through the ports 62, and be discharged directly above the spreader 25. In the upward movement of the valve 56, it is apparent that the plunger 22, being united thereto, will be caused to rise in its cavity, and thus force gasoline therefrom through the channel 23, and port 30, in the spreader. As soon as the suction in the mixing chamber is overcome, the spring 78, which is interposed between the valve 56, and the casing 14, will force said valve and piston downwardly, in which operation gasoline will be drawn through the ports 41, 40, and 42, into the cavity 21, of

the pump cylinder, after which, the above-named operation will be repeated.

To prevent the pump discharging excessive quantities of gasoline into the mixing chamber 59, the channels 32, 33, and 34, in the upper portion of the pump cylinder are employed, for it is apparent that the surplus gasoline will be forced downwardly through said channels and back into the receptacle or reservoir 15, from which it will again be drawn into the pump.

Instead of using a plate valve 56, of the construction shown in Fig. 1, of the drawings for the upper end of the air chamber or cylinder 10, the construction shown in Fig. 5, may be used, in the operation of which, it will be understood that as the valve 56, is raised, the flange 57, will open the ports 77, and permit air to pass therethrough, and from thence through the ports 62, by means of which it will be directed toward the top of the spreader 25, and below the baffle 65, on the needle valve 31, which regulates the quantity of gasoline discharged by the pump into the mixing chamber.

Having thus fully described my invention what I claim as new and desire to secure by Letters-Patent is—

1. A carbureter consisting of a main casing having a mixing chamber at one end thereof, means at its other end to admit air thereto, a reservoir within the casing, a pump within the reservoir having a valve-controlled intake port communicating therewith and a valve-controlled discharge port communicating with the mixing chamber, and a spring-actuated valve connected to the plunger of the pump to open and close one end of the main casing.

2. A carbureter consisting of a main casing having a mixing chamber at one end thereof, means at its other end to admit air thereto, a reservoir within the casing, a pump within the reservoir having a valve-controlled intake port communicating therewith and a valve-controlled discharge port communicating with the mixing chamber, and also having a valve-controlled by-pass communicating at its upper end with the upper portion of the discharge port and at its lower end with the reservoir, and a spring-actuated valve connected to the plunger of the pump to open and close one end of the main casing.

3. A carbureter consisting of a main casing having a mixing chamber at one end thereof, means at its other end to regulate the admission of air thereto, a reservoir within the casing, a pump within the reservoir extended therethrough and into the mixing chamber, said pump having a valve-controlled intake port communicating with the reservoir and a valve-controlled discharge port communicating with the mixing chamber, and a spring-actuated valve mov-

ably mounted on the pump cylinder and connected to the plunger of the pump to open and close one end of the main casing.

4. A carbureter consisting of a main casing having a mixing chamber at one end thereof, means at its other end to admit air thereto, a reservoir within the casing, a pump within the reservoir extended therethrough and into the mixing chamber, said pump having a valve-controlled intake port communicating with the reservoir, and a valve-controlled discharge port communicating with the mixing chamber, and also having a valve-controlled by-pass communicating at its upper end with the upper portion of the discharge port and at its lower end with the reservoir, and a spring-actuated valve connected to the plunger of the pump to open and close one end of the main casing.
- 10 5. A carbureter consisting of a main casing having a mixing chamber at one end thereof, means at its other end to admit air thereto, a reservoir within the casing, a pump cylinder within the reservoir having a valve-controlled intake port communicating therewith and a valve-controlled discharge port communicating with the mixing chamber, an apertured spreader on the discharge end of the cylinder, a valve to regulate the flow of liquid through the opening in the spreader, and a spring-actuated valve connected to the plunger of the pump to open and close one end of the main casing.
- 15 6. A carbureter consisting of a main casing having a mixing chamber at one end thereof, means at its other end to admit air thereto, a reservoir within the casing, a pump cylinder within the reservoir having a valve-controlled intake port communicating therewith and a valve-controlled discharge port communicating with the mixing chamber, and also having a valve-controlled by-pass communicating at its upper end with the upper portion of the discharge port and at its lower end with the reservoir, an apertured spreader on the discharging end of the cylinder, a valve to regulate the flow of liquid through the opening in the spreader, and a spring-actuated valve connected to the plunger of the pump to open and close one end of the main casing, said valve having an annular flange extended into the main casing and provided with inwardly and upwardly directed ports.

7. A carbureter consisting of a main casing having a mixing chamber at one end thereof, means at its other end to regulate the admission of air thereto, a reservoir within the casing, a pump cylinder within the reservoir having a valve-controlled intake port communicating therewith and a valve-controlled discharge port communicating with the mixing chamber, an apertured spreader on the discharge end of the cylinder, a valve to regulate the flow of liquid through the opening in the spreader, a baffle on said valve, and a spring-actuated valve connected to the plunger of the pump to open and close one end of the main casing.

7. A carbureter consisting of a main casing having a mixing chamber at one end thereof, means at its other end to regulate the admission of air thereto, a reservoir within the casing, a pump cylinder within the reservoir having a valve-controlled intake port communicating therewith and a valve-controlled discharge port communicating with the mixing chamber, and also having a valve-controlled by-pass communicating at its upper end with the upper portion of the discharge port and at its lower end with the reservoir, an apertured spreader on the discharging end of the cylinder, a valve to regulate the flow of liquid through the opening in the spreader, and a spring-actuated valve connected to the plunger of the pump to open and close one end of the main casing.
